UNITED STATES PATENT OFFICE.

PAUL H. McCAIN, OF CHICAGO, ILLINOIS, ASSIGNOR TO ECONOMY SCREW CORPORATION, OF CHICAGO, ILLINOIS, A CORPORATION OF ILLINOIS.

MACHINE FOR FEEDING NUT BLANKS AND THE LIKE.

Application filed October 30, 1925. Serial No. 65,869.

This invention relates to improvements in machines for feeding blanks, such as nut blanks, washers and the like, regardless of their shape, to a machine where further operation is to be performed on them, and has more particular reference to mechanism embodying a hopper like receptacle into which a number of blanks are indiscriminately thrown and from which hopper the blanks are automatically delivered and substantially continuously by means of a rotatable element operating within the hopper and having a constant direction of motion.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention, and in which

Figure 1 is a side elevation of a machine of this character constructed in accordance with the principles of this invention.

Figure 2 is a sectional view taken on line 2—2, Figure 1.

Figure 3 is a sectional view taken on line 3—3, Figure 2.

Figure 4 is a detail sectional view taken on line 4—4, Figure 3, with parts omitted.

Figure 5 is a detail view partly in elevation and partly broken away, taken on line 5—5, Figure 3.

Figure 6 is an enlarged detail top plan view of Figure 5, with parts omitted and partly broken away.

Figure 7 is a sectional view taken on line 7—7, Figure 5.

Referring more particularly to the drawings the numeral 10 designates generally a hopper of any desired size and configuration and is supported by a suitable base 11.

Projecting above the hopper are spaced uprights 12—13, and between these uprights a feeding device is arranged.

The uprights 12 and 13 are preferably spaced from the sides of the hopper and are constructed so as to form openings 14—15 and between which uprights a rotary pick up device operates.

The pick up device preferably consists of two disc like elements 16—17, one of which is provided with gear teeth 18.

The discs 16 and 17 are each provided

with radially arranged arms or surfaces 19, and the arms 19 of the respective elements 16 and 17 are laterally spaced from each other by means of a spacing member 20. This spacing member 20 is provided with radially arranged arms 21 which stand between the arms 19 of the elements 16—17, and the elements 16, 17 and 20 are secured together in any desired or suitable manner such as by means of fastening devices 22. One face 23 of the arms 21 of the element 20 terminates below the adjacent faces 24 of the arms 19 of the elements 16 and 17 so as to form a recess between the elements 16 and 17, and in which recess the blanks 25 rest and travel to be feed by the pick up device through the ends of the arms 19.

The feeding device thus formed is supported in any suitable manner preferably by means of rollers 26—27, the roller 27 being provided with gear teeth 28 which mesh with the gear teeth 18 on the element 16 for rotating the pick up device. Motion is transmitted to the gear 27 from any suitable source, not shown.

Any number of arms 19—21 may be provided and are so arranged that when the elements 16—17 are rotated said arms will pass into the hopper 10 and pick up the articles contained therein.

The surfaces 24 of the arms 19, and 23 of the arms 21 are preferably curved and the supporting surface 23 of the arms 21 are formed within openings or spaces 29 between adjacent pairs of arms so that when the elements 16—17 are rotated the arms will pass into the hopper 10 and the blanks 25 (see Figure 3) which are in the hopper will pass into the opening 29 as the latter moves adjacent the bottom of the hopper and the blanks will fall into the grooves or recesses 19 in the arms in such a manner that they will rest upon the bottom of the groove formed by the surface 23 of the arms 21 on the element 20.

As the elements 16—17 or pick up device rotates in the direction indicated by the arrow, the blanks which have been picked up by one of the arms will gradually move across the bottom 23 of the groove in the arm in a direction toward the axis of rotation of the pick up device, the blanks being discharged or delivered from the arms by gravity and at a predetermined point in the cycle of operation of the device.

Any number of these arms may be provided and they project inwardly from the periphery of the elements 16—17 and terminate considerably short of the axis of rotation of the element.

Co-operating with the arms of the pick up device is a disc like element 31 which is disposed adjacent the axis of the elements of the pick up device and is of a diameter 10 that its periphery will be disposed adjacent the free extremities of the arms of the pick up device. This disc like element 31 is mounted upon a fixed support 32.

Secured to the lateral face of the disc 31 is a member 33 which is held in position in any suitable manner such as by means of fastening devices 34 in the form of bolts which pass through the member 33 and also through suitable slots 35 in the disc 31.

20 The exposed lateral face of the member 33 is cut away so that it will be beveled or inclined as at 36. Carried by the member 33 and abutting the inclined face 36 is a receiver 37, having a slot 38 for receiving the blanks from the pick up device and for delivering the blanks into a raceway 39. The raceway 39 is supported in any suitable manner and passes through an aperture 40 in the wall of the hopper 10. The raceway 39 is independent of the receiver 37 and the extremity of the raceway is disposed in close proximity to the end of the receiver through which the slot or channel 38 passes and in such a position that when the receiver 37 is in the position shown in Figure 5, with respect to the raceway 39, the latter will form a continuation of the slot in the receiver 37. When the parts are in this position the blanks 25 will be delivered from the slot 19 40 in the arms of the pick up device by gravity and pass into the slot or channel 38 and will be delivered from the receiver into the raceway 39.

It will be noted that the receiver 37 is mounted adjacent the inclined face 36 of the member 33, which will cause the slot or channel 38 of the receiver to be disposed at an angle or in an inclined position with respect to the axis of rotation of the pick up device, and as the inner or receiving end of the raceway 39 is also disposed adjacent this surface 36, the raceway will also be inclined to the axis of rotation of the pick up device so that the blanks will be fed 55 in a substantially straight line after they leave the arms of the pick up device until they are delivered out of the hopper.

The receiver 37 is positioned so that the blanks 25 will be delivered thereto from the 60 slots or grooves 19 in the arms of the pick up device at a predetermined point in the operation of the pick up device so that the blanks will be fed by gravity.

When it is desired to vary the time in 65 the cycle of operation of the pick up device

or the point at which the receiver 37 receives the blanks from the arms of the pick up device, the fastening devices 34 may be loosened and the member 33 together with the receiver 37 may be axially rotated with 70 respect to the supporting disc 31, the slots 35 permitting such rotation, until the receiving end of the receiver 37 has been adjusted to the point at which it is desired that the blanks 25 shall be delivered thereto 75 from the arms of the pick up device. The inner extremity of the supporting surface of the receiver 37 being disposed in close proximity to the inlet of the raceway 39, it will be manifest that the blanks 25 will 80 readily pass from the receiver 37 into the raceway 39 and in any position to which the receiver 37 may be adjusted. A cover plate 40 may be provided for the raceway 39.

Arranged in proximity to the inlet end 85 of the raceway 39 is a clearance device preferably embodying a rotatable element 41 provided with spirally arranged peripheral threads. This clearance device also preferably embodies a toothed element 42 rotatable therewith and the two are mounted 90 upon a shaft 43 for rotation therewith.

The shaft 43 is mounted in a suitable bearing 44 and in a position that the axis of the shaft will be inclined to the axis of rotation of the pick up device so as to properly position the element 41 with respect to the raceway 39. The threads on the element 41 are so arranged that by rotation of the element in the direction indicated 100 by the arrows in Figure 5, the blanks which have accumulated at the entrance of the raceway will be fed laterally away from the raceway and will be delivered back into the hopper 10.

The element 42 may be employed, if desired, to assist in removing the surplus blanks from the top of the raceway and deliver them back into the hopper.

In order to permit the shaft 43 to be disposed at this angle the member 33 is provided with a slot 45 and the element 31 may be provided with a slot 46, and through which slots the shaft 43 passes. These slots are of such a size and shape that the rotation or adjustment of the member 33 with respect to the supporting disc 31 will not be interfered with.

The clearance device 41 may be raised and lowered with respect to the raceway to compensate the difference in sizes of blanks fed by the machine, in any suitable manner, but is preferably accomplished by mounting the bearing 44 of the shaft 43 in a manner that it may be bodily adjusted.

To that end the support 32 may be provided with a suitable face against which the face of the bearing 44 rests. The support 32 may be provided with grooves 47 for receiving lugs 48 that are carried by 130

the bearing so as to insure the proper movement of the bearing 44 during its adjustment and for maintaining the shaft 43 in proper position.

5 Fastening devices 49, such as screws or bolts, may be provided for securing the bearing 44 in its adjusted position. Obviously the wall of the hopper 10 and the portion of the support 32 through which the 10 shaft 43 passes are provided with slots to permit of such adjustment.

The shaft 43 is rotated in any desired or suitable manner preferably by means of an endless belt 50 passing over a pulley 51 on 15 the shaft 43 and also a pulley 52, the latter being connected with a pulley 53 for rotation therewith, and the pulley 53 receives its motion from a suitable source through the medium of a belt 54.

20 As a means for assisting in feeding the blanks down the raceway 39, which latter is inclined so that the blanks will move therethrough from the hopper, there may be a tappet or tapping device provided 25 which may be of any suitable construction. The device here shown for accomplishing this purpose embodies a shaft 55 which is mounted in suitable bearings 56-57 so that the end 58 of the shaft will be disposed 30 adjacent one of the walls of the raceway 39. A cushioning device 59 may be provided on the extremity of the shaft and is adapted to engage the wall of the raceway.

The shaft is rotated in any suitable manner such as by means of an endless belt 60 35 passing over a pulley 61 on the shaft and over a pulley 62 which is preferably connected with the pulley 52 for rotation therewith.

40 The bearings 56 and 57 are spaced and secured to the shaft 55 for rotation therewith is a collar 63, having a cam device 64 formed thereon, and the adjacent face of the bearing 57 is provided with spaced projections 45 65 adapted to engage the cam 64.

Interposed between the bearing 56 and the collar 63 is an elastic device 66 such as a coil spring which has engagement at one end with the bearing 56 and at its other end 50 with the collar 63.

The shaft 55 is also movable longitudinally in its bearings and the stress of the spring 66 is such that it tends normally to move the extremity of the shaft 55 into engagement with the wall of the raceway 39.

60 As the shaft 55 is rotated the cam 64 will engage the projections 65 on the bearing 57 and will ride thereover. This will contract the spring 66 and when the cam 64 has passed out of engagement with one of the projections 65, the spring 66 will expand and will forcibly move the extremity of the shaft 55 into contact with the wall of the raceway 39.

65 Any number of projections may be pro-

vided according to the number of blows that it is desired to impart to the raceway.

While the preferred form of the invention has been herein shown and described it is to be understood that various changes 70 may be made in the details of construction and in the combination and arrangement of the several parts, within the scope of the claims, without departing from the spirit of this invention. 75

What is claimed as new is:—

1. In a device of the nature described, in combination, hopper means, pick-up means for picking up devices from said hopper means, said pick-up means comprising a rev- 80 oluble member having means providing a plurality of troughs extending from near the periphery of said revoluble member to regions short of the axis of said revoluble member, the inner extremities of said troughs being disposed in the periphery of a circle, the center of which is located in the axis of rotation of said revoluble member, and delivery means disposed at an angle to the plane of rotation of said revoluble mem- 90 ber and having its extremity closely adjacent to the inner extremities of said troughs as said troughs rotate with said revoluble member, tapping means for said delivery means, a screw cooperatively associated with 95 said delivery means, and means for operating said tapping means and for turning said screw in a direction to move devices in engagement with said screw transversely of said delivery means. 100

2. In a device of the nature described, in combination, hopper means, pick-up means for picking up devices from said hopper means, said pick-up means comprising a rev- 105 oluble member having means providing a plurality of troughs extending from near the periphery of said revoluble member to regions short of the axis of said revoluble member, the inner extremities of said troughs being disposed in the periphery of a circle, the center of which is located in the axis of rotation of said revoluble member, the bottoms of said troughs being curved op- 110 positely to the direction of rotation of said revoluble member, delivery means disposed at an angle to the plane of rotation of said revoluble member and having its extremity closely adjacent to the inner extremities of said troughs as said troughs rotate with said revoluble member, tapping means for 115 said delivery means, a screw cooperatively associated with said delivery means, and means for operating said tapping means and for turning said screw in a direction to move devices in engagement with said screw transversely of said delivery means. 120

3. In a device of the nature described, in combination, hopper means, pick-up means for picking up devices from said hopper means, said pick-up means comprising a rev- 125

130

oluble member having means providing a plurality of troughs extending from near the periphery of said revoluble member to regions short of the axis of said revoluble member, the inner extremities of said troughs being disposed in the periphery of a circle, the center of which is located in the axis of rotation of said revoluble member, delivery means disposed at an angle to the plane of rotation of said revoluble member and having its extremity closely adjacent to the inner extremities of said troughs as said troughs rotate with said revoluble member, tapping means for said delivery means, a screw cooperatively associated with said delivery means, and simultaneously operating means for operating said tapping means, for turning said screw and for revolving said revoluble means.

4. In a device of the nature described, in combination, hopper means, pick-up means for picking up devices from said hopper means, said pick-up means comprising a revoluble member having means providing a plurality of bottomed troughs extending

from near the periphery of said revoluble member to regions short of the axis of said revoluble member, the inner extremities of said troughs being disposed in the periphery of a circle, the center of which is located in the axis of rotation of said revoluble member, the bottoms of said troughs being curved oppositely to the direction of rotation of said revoluble member, delivery means disposed at an angle to the plane of rotation of said revoluble member and having its extremity closely adjacent to the inner extremities of said troughs as said troughs rotate with said revoluble member, tapping means for said delivery means, a screw cooperatively associated with said delivery means, and simultaneously operating means for operating said tapping means for turning said screw and for revolving said revoluble means.

In testimony whereof I have signed my name to this specification, on this 28th day of October, A. D. 1925.

PAUL H. McCAIN.
